UNITED STATES PATENT OFFICE.

JOHN DOBROWOLSKI, OF CHICAGO, ILLINOIS.

RAIL-JOINT.

1,298,675.

Specification of Letters Patent.

Patented Apr. 1, 1919.

Application filed May 6, 1918. Serial No. 232,778.

To all whom it may concern:

Be it known that I, JOHN DOBROWOLSKI, former citizen and inhabitant of Russia, Poland, who have declared my intention of 5 becoming a citizen of the United States, and a resident of the city of Chicago, county of Cook, and State of Illinois, have invented certain new and useful Improvements in Rail-Joints, of which the following is a 10 specification.

My invention relates to improvements in rail joints, and has for its object the production of a rail joint designed for use in the connection of a switch tongue with the co-operating rail, whereby the switch tongue will be yieldingly held in a fixed position so as to allow for yielding of the same in order to permit of the passage of a train from a switch or branch track onto a main track 20 without thereby causing the switch to be opened.

A further object is the production of a rail joint as mentioned, which will be of durable and economical construction and 25 highly efficient in use.

Other objects will appear hereinafter.

The invention consists in the combinations and arrangements of parts hereinafter described and claimed.

30 The invention will be best understood by reference to the accompanying drawings forming a part of this specification, and in which:

Figure 1, is a top plan view of a section 35 of track, the rails of which are equipped with connections, embodying the invention,

Figs. 2 and 3, are perspective views of the members of the joint which are applied to the stationary rail,

40 Figs. 4 and 5, are perspective views of the members of the joint applied to the switch tongue,

Fig. 6, is an enlarged top plan view of a section of rail at the switch joint therein,

45 Fig. 7, is a view similar to Fig. 6, with parts broken away and shown in section to better illustrate the construction,

Fig. 8, is a section taken on line 8—8 of Fig. 6, and

50 Fig. 9, is a perspective view of one of the fastening bolts included in the construction.

The preferred form of construction, as illustrated in the drawings, is designed for use in connection with a switch tongue 10

and the stationary rail 11, from which and 55 in alinement with which the switch tongue extends.

The joint comprises two reinforcing members 12 arranged on opposite sides of the rail 11, the members 12 being formed to snugly 60 embrace the flange and base of the rail, each of said members being provided with a laterally extending base portion 13 which is perforated for the accommodation of fastening spikes. Each of said members 12 is also 65 formed with a base portion 14 adapted to engage under the rail, the adjacent inner edges of the base portions 14 being adapted to overlap, as clearly seen in Figs. 2, 3 and 8. The base portions 14 are formed with exten- 70 sions 15, and the extensions 15 are provided at their outer ends with lateral extensions 16 which are also perforated for the accom- modation of fastening spikes.

To the opposite sides of the switch tongue 75 are applied reinforcing members 17 of a form corresponding with the members 12, except that the members 17 are not provided with base portions. The members 17 are free, being permitted to slide upon the ex- 80 tensions 15 and 16 of the members 12 in the pivotal movement of the switch tongue.

Extending between and connecting the members 12 and 17 are elongated resilient bars 18, which engage with dove-tailed slots 85 19 and 20 provided respectively in the members 12 and 17, as clearly seen in Figs. 2, 3, 4 and 5. The extreme outer ends of the bars 18 engage with recesses or pockets 21 formed in the switch tongue, as clearly seen in Fig. 90 7. The bars 18 are adapted to yieldingly hold the switch tongue in fixed position, permitting, however, of yielding of the tongue from this position under pressure.

Aiding the bars 18 in the yielding retention of the switch tongue in a fixed position are elongated leaf springs 22, which are arranged in slots 23 provided for the reception thereof in the extensions 15 of the members 12, as clearly seen in Figs. 2, 3 and 7. The 100 free ends of the springs 22 are formed with upwardly extending lugs 22', which engage in notches 24 formed at the under sides of reinforcing members 17 of the switch tongue, said springs 22 being so arranged as 105 to exert pressure upon the members 17 such as will yieldingly hold the switch tongue in the fixed position above referred to.

With this arrangement, when the construction is in use, the members 18 and 22 at one side of the rail will be brought into play in order to hold the switch tongue in the desired fixed position, but by employing resilient members at both sides of the joint, as used herein, the joint is rendered applicable for use with switch tongues operating in either direction, and at the same time the 10 spring members 18 and 22 at one side of the joint will always serve as a cushion in the return movement of the switch tongue, after the latter has been forced from its fixed position.

15 This construction insures a switch at a branch or switch track being always closed, so as to avoid the possibility of a fast train traveling along the main track running into an open switch. With the construction set forth, in the event of a train running from the switch or branch track onto the main track, the switch tongue will yield under the pressure of the flanges of the 20 wheels and allow the train to pass, the switch tongues, however, being instantly returned to their closed positions after the passage of the train, under the influence of the resilient members coöperating therewith.

The members 12 and 17 are secured to the 30 rails by bolts 25, which pass through said members and the webs of the rails, as clearly seen in Fig. 8. The bolts 25 are formed at their outer ends with slots 26 all of the bolts coöperating with the stationary rail, or the 35 switch tongue being engaged by a single key 27 which is adapted to pass through the slots 26 in said bolts, as clearly seen in Fig. 6. In order to hold the bolts against rotary movement and in a position in which the slots 26 40 will be in alinement, that is, extend horizontally, the bolts are formed with laterally extending tongues 28 which engage with corresponding notches 29 provided for the reception thereof in the openings for said bolts 45 in the reinforcing members at one side of the rail, as clearly seen in Figs. 3 and 5.

While I have illustrated and described the preferred form of construction for carrying my invention into effect, this is capable of 50 variation and modification without departing from the spirit of the invention. I, therefore, do not wish to be limited to the precise details of construction set forth, but desire to avail myself of such variations and 55 modifications as come within the scope of the appended claims.

Having described my invention, what I

claim as new and desire to secure by Letters Patent is:—

1. The combination of a stationary rail; a 60 switch tongue arranged in alinement with said rail; and resilient means extending between and connecting said rail and tongue for yieldingly holding the latter in a fixed position, substantially as described. 65

2. The combination of a stationary rail; a switch tongue arranged in alinement with said rail; and elongated resilient members extending between and connecting said rail and tongue for yieldingly holding the latter 70 in a fixed position, substantially as described.

3. The combination of a stationary rail; a switch tongue arranged in alinement with said rail; reinforcing members embracing said rail and tongue; and elongated resilient members extending between and connected with said reinforcing members for yieldingly holding said switch tongue in a 75 fixed position, substantially as described.

4. The combination of a stationary rail; a 80 switch tongue arranged in alinement with said rail; reinforcing members embracing said rail and tongue; and elongated resilient members extending between and in dove-tail connection with said reinforcing members, 85 for yieldingly holding the switch tongue in a fixed position, substantially as described.

5. The combination of a stationary rail; a switch tongue; and means for yieldingly holding said switch tongue in a fixed position, 90 said means comprising resilient members coöperating with the bases and sides of said rail and tongue, substantially as described.

6. The combination of a stationary rail; a switch tongue arranged in alinement with said rail; reinforcing members secured to the sides of said rail, having base portions extending beyond the end of the rail; reinforcing members applied to the sides of said 100 tongue, slidably mounted on said base portions; and elongated resilient members extending between and connected with said reinforcing members for yieldingly holding the latter in a fixed position, substantially as 105 described.

In testimony whereof I have signed my name to this specification in the presence of two subscribing witnesses.

JOHN X DOBROWOLSKI.
